Brown & Bigelow, St. Paul, Minn.

Application December 2, 1955, Serial No. 39,139

Term of patent 7 years

(Cl. D22—5)

FIG. 1

FIG. 2

FIG. 3

The dominant features of my design reside in the handle portions shown in solid lines in Figures 2, 3 and 4 on the drawing.

I claim:

The ornamental design for scissors or the like, as shown and described.
